7 Claims

ABSTRACT OF THE DISCLOSURE

A lock having a locking bar with spaced slots extending over a portion of its length and an abutment to be inserted behind a portion of one of the members to be locked, and a guard plate which has an opening to receive the bar, and be secured thereto, the plate engaging the outside of the members, and a locking plate, carried in sliding relation, by the guard plate, and with a finger which engages one of said slots to lock the plate to the locking bar.

The present application constitutes a continuation-in-part of my two earlier applications, Ser. Nos. 552,553 and 615,651.

This invention relates to portable locks, primarily for travel purposes, for closet, desk and dresser drawers in hotel rooms, and for a variety of other purposes and which employs a padlock for the locking element. The lock of the present invention may also be used as a supplemented lock for an apartment house door in place of chain locks which are not too satisfactory. The device of the present invention employs an elongated locking bar with a hook shaped abutment at one end which is inserted in a strike plate opening in a door frame and extends forwardly through the space between the door and frame, the locking bar having spaced slots extending over a portion of its length, one of which is engaged by a locking finger on a locking plate which holds the members in locked relation. This locking plate is mounted in sliding relation to a second or guard plate having an opening to receive the locking bar in snug but free sliding relation. Both the locking plate and guard plate have apertured lugs which overlie each other when the plates are in coincidence and the fringe secures the bar to the plates. A locking device such as a padlock, where shackle passes through the apertures in the lugs, secures the parts in locked relation.

In my earlier applications above referred to, the locking bar was provided with teeth or notches extending along one or both longitudinal edges, the teeth being engaged by opposed edges of a slot formed in the locking plate, thus securing the locking plate and its related guard plate against movement on the locking bar.

The improved lock of the present invention employs a locking bar with spaced transverse abutments which may be conveniently formed as through slots in side-by-side relation longitudinally of the bar, one of which receives a projection formed on or carried by the locking plate. The locking plate may thus have an opening of special configuration formed therein by punching or otherwise and leaving a projecting finger and sufficient space beyond the free end of the finger for the locking bar to pass therethrough.

This provides an exceedingly simple construction wherein close-fit tolerances are easier to meet and the dies required for stamping out the plates are inexpensive to construct.

In addition to the improved locking bar of the present application, the guard plate with its opening to receive the locking bar is also improved by extending this open-

2

ing clear to the edge to make it far easier to slide the guard plate, from the side, onto the locking bar. The locking plate has a similar side opening and they both are aligned when the plates are applied to the bar.

In the drawing:
5 FIG. 1 is a broken horizontal section taken from a door and frame, and showing the lock of the present invention with the parts in locked position;

10 FIG. 2 is a front elevation thereof;
FIG. 3 is an elevation of the rear face of the locking assembly;

15 FIG. 4 is a section on line 4—4 of FIG. 3;
FIG. 5 is a view similar to FIG. 3 but shows the locking plate in extended position;

20 FIG. 6 is a perspective view of the locking bar.
FIG. 7 is a view similar to FIG. 3 but showing a modification wherein the plates have openings for the locking bar, these openings extending clear to the edge.

The lock of the present invention includes a flat hook bar 10, a guard plate 11 having a rectangular opening 12 to receive the bar in snug but free sliding relation and a locking plate 14 carried by the guard plate in free sliding, face-to-face relation. The hook bar has a laterally extending hook-like abutment 16 at its inner end which is received in an opening 18 in a strike plate 19 in a fixed door frame 20. This door frame has an opening 21 which is generally aligned with opening 18 and normally receives a spring-urged latch bolt extending from a lock (not shown) in a door 22. There is normally a slight space or clearance shown at 24 between a hinged door and door frame which is sufficient to receive the thin flat locking bar. The guard plate 11 is positioned normal to the major axis of the locking bar at all times and the locking plate is mounted in sliding face-to-face relation to the guard plate and has a locking finger 26 which passes into one of a plurality of generally rectangular slots 28 extending over the major portion of the length of the locking bar. The opposed vertical edges of each slot 28 are regarded herein essentially as abutments and the finger 26 as a fixed stop, engaging one of the abutments to restrain movement of the locking plate relative to the locking bar.

In the arrangement shown, the guard plate component referred to in the claims as a guard plate structure, is essentially two plates with a cavity therebetween in which locking plates slide. Thus it includes an outer wall 29 and an inner wall 30, and can be stamped out from a single piece of sheet metal, the plate walls are joined together in spaced relation along their lower edges by a short lower wall 31 to form a narrow longitudinal cavity 32 to receive the locking plate in sliding relation therebetween. At its upper edge, wall 29 is joined to wall 30 by an overturned edge 34 and the meeting faces secured together as by welding or brazing.

The plate structure 11 with its spaced inner and outer walls with a long cavity 32 therebetween to receive the locking plate 14 in sliding relation, is termed a guard plate because one of its walls, i.e., its inner wall 30, together with flange 34, engages the door frame 20 and the door 22, with the locking bar and its hook 16 securely holding the assembly against both door and frame and acts as a guard or stop to prevent the door from opening.

65 The inner wall 30 has an opening 36 identical with and aligned with opening 12 in outer wall 29, and the latter has a struck out section which is bent forwardly, i.e., towards the operator, at right angles to the wall, to form a locking lug 38 with a hole 39. The locking plate has a similar struck out section 40 which is bent forwardly and overlies lug 38 when the plates are in coincidence and in this position the holes also are in coincidence and receive the shackle 41 of a simple padlock 42. In this way, no metal need be removed to form the lugs except that which is punched out to form holes 39.

The locking finger 26 is also formed by a punching operation but in this instance enough metal is removed to form a hole 44 in the locking plate, deep enough to receive the locking bar in vertical position and wide enough to enable the plate to move from the position of FIG. 3 where the finger is in one of the slots 28 where it performs its secure locking function, to the position of FIG. 5, where the finger is away from the locking bar and the latter is free to move in slot 12. The locking plate is moved by grasping lug 40 and moving it to the right, when viewed as in FIG. 5, until vertical edge 46 contacts a pin 48 passing through the inner and outer walls of the guard plates. This pin limits travel of the locking plate to the right and travel to the left is stopped when flange 43 of lug 40 contacts edge 49 of wall 11.

To apply the lock, locking bar 10 is positioned between door and frame as in FIG. 1 and the locking plate moved to the right as in FIG. 5 to open the passages in the guard and locking plate assembly for free sliding horizontal movement of the locking bar thereon. When the assembly contacts the door and frame as in FIG. 1, the locking plate is moved to the left to put the plates and lugs in coincidence and the padlock applied.

A slight modification is shown in FIG. 7 wherein even this horizontal movement is eliminated. The front and rear walls of the guard plate have aligned slots shown at 50 which are continuations of the opposed vertical edges of opening 12 shown in FIG. 2. The locking plate also has a slot 51 whose left hand edge is a continuation of edge 45 forming part of opening 44. When the locking plate is moved to the left, and the two plates are, therefore, out of coincidence, slots 50 and 51 are in coincidence and it is simply necessary only to move the plate assembly against the door and frame (the position of FIG. 1, but above the locking bar) and then move it downward about $\frac{1}{2}$ inch, slide the plates into coincidence, and apply the lock.

The embodiments of the invention in which an exclusive property or privilege is claimed are defined as follows:

1. A portable auxiliary locking device for doors, drawers and the like which are mounted in frames and including an elongated thin hook bar provided at its inner end with a laterally offset portion forming a hook to be received in an opening in one of the members to be locked relative to the other, said hook bar also provided with a plurality of spaced abutments disposed longitudinally of the bar, a guard plate structure carried on and perpendicular to said hook bar and comprising inner and outer plates and means for maintaining said plates in spaced relation to form a slideway therebetween, said plates hav-

- ing aligned openings shaped to receive the hook bar in close fitting but free sliding relation, and means for securing the guard plate structure in locked relation to the bar, said means including a locking plate mounted for free-sliding limited movement in said slideway, said locking plate having a projection which, in a first position of said plate, engages one of said abutments and locks said plate and bar against relative movement and which in a second position permits free relative movement, and means for securing the locking plate in said first position.
- 5 2. The structure recited in claim 1 wherein the hook bar is formed with a plurality of through slots extending transversely thereof and whose opposed edges form said abutments.
- 10 3. The structure recited in claim 2 wherein the locking plate has an opening of special configuration providing a finger-like element forming the projection which passes through one of said slots whose edges engage the finger.
- 20 4. The structure recited in claim 1 wherein overlying apertured lugs extend from one side of the locking plate and the guard plate structure, and locking means, for securing the plates in said first position, extending through the apertures therein.
- 25 5. The structure recited in claim 4 wherein the locking means is a padlock.
6. The structure recited in claim 1 wherein the plates are substantially in coincidence when they are in said first position and the locking plate has been moved out of coincidence when they are in said second position.
- 30 7. The structure recited in claim 6 wherein the openings in the guard plate structure extend clear to one edge of said structure, forming a side opening and wherein the locking plate has an opening coinciding therewith when the plates are in said second position, thus forming a second side opening, so as to permit the plates to be applied to the locking bar by moving the latter through said side openings.
